(57) **CLAIM**

The ornamental design for a face mask, as shown and described.

DESCRIPTION

FIG. 1 is a perspective view of a first embodiment of a face mask, showing our new design;

FIG. 2 is a side perspective view thereof;

FIG. 3 is a front elevational view thereof, the rear view being a mirror image thereof;

FIG. 4 is a top plan view thereof;

FIG. 5 is a bottom plan view thereof;

FIG. 6 is a right side view thereof;

FIG. 7 is a left side view thereof;

FIG. 8 is a side perspective view thereof, shown in an environment of use;

FIG. 9 is a front view thereof, shown in an environment of use; and

FIG. 10 is a side perspective view thereof, shown in an environment of use.

FIG. 11 is a perspective view of a second embodiment of a face mask;

FIG. 12 is a side perspective view thereof;

FIG. 13 is a front elevational view thereof, the rear view being a mirror image thereof;

FIG. 14 is a top plan view thereof;

FIG. 15 is a bottom plan view thereof;

FIG. 16 is a right side view thereof; and

FIG. 17 is a left side view thereof.

FIG. 18 is a perspective view of a third embodiment of a face mask;

FIG. 19 is a side perspective view thereof;

FIG. 20 is a front elevational view thereof, the rear view being a mirror image thereof;

FIG. 21 is a top plan view thereof;

FIG. 22 is a bottom plan view thereof;

FIG. 23 is a right side view thereof;

FIG. 24 is a left side view thereof;

(Continued)

FIG. 25 is a side perspective view thereof, shown in an environment of use; and

FIG. 26 is a front view thereof, shown in an environment of use.

FIG. 27 is a perspective view of a fourth embodiment of a face mask;

FIG. 28 is a side perspective view thereof;

FIG. 29 is a front elevational view thereof, the rear view being a mirror image thereof;

FIG. 30 is a top plan view thereof;

FIG. 31 is a bottom plan view thereof;

FIG. 32 is a right side view thereof; and,

FIG. 33 is a left side view thereof.

The broken line showing a human in FIGS. 8-10, 25, and 26 depicts environmental subject matter and forms no part of the claimed design.
